UNITED STATES PATENT OFFICE.

TURE GUSTAF RENNERFELT, OF STOCKHOLM, SWEDEN.

STONE-CRUSHING MACHINE.

1,358,682.

Specification of Letters Patent.

Patented Nov. 9, 1920.

Application filed July 6, 1918. Serial No. 243,649.

To all whom it may concern:

Be it known that I, TURE GUSTAF RENNERFELT, a subject of the King of Sweden, and resident of Stockholm, in the city of 5 Stockholm and kingdom of Sweden, have invented certain new and useful Improvements in Stone-Crushing Machines, of which the following is a specification.

My invention relates to improvements in a 10 stone crushing machine of the type in which stones, ore and similar material are crushed between a stationary jaw and a movable jaw to which a swinging or oscillating movement is transmitted from a driving shaft, 15 journaled in the frame of the machine.

As such machines are generally constructed they suffer from the following faults: Their mechanical efficiency is low, frequently less than 50%, they lack a reliable 20 safety arrangement against overload, and their bearings and journals are subjected to considerable wear and heating. The wear and heating of the bearings is a necessary consequence of the low efficiency, 25 since as much as half of the energy supplied to the machine may be consumed in friction. But the evil in this respect is frequently increased by the fact that some of the bearings of the machine become exposed 30 to abnormally high pressures for the reason that they are not in accurate alinement, the construction of the machine being such that standard machine tools cannot readily be used for the finishing of all the bearings. 35 The object of my invention is to remedy the above mentioned faults and to produce a stone crushing machine of high mechanical efficiency, having a reliable safety arrangement against overload and of such construction 40 that all its bearings can be machined into perfect alinement.

My invention is illustrated in the accompanying drawing in which Figure 1 shows a vertical sectional view of the machine, Fig. 45 2 is a plan view of a detail referred to in the specification as a segment or thrust bar, Fig. 3 is a cross sectional view along the line $x-x$ of Fig. 2, Fig. 4 is a side view of a detail called the lever as seen in the direction of the arrow in Fig. 1, and Fig. 5 is a detail view of a part termed the safety bolt.

Referring to the drawing in detail, 2 represents the frame of the crusher, 3 the stationary crushing plate, and 4 the other 50 crushing plate fastened to the movable jaw 5 which is journaled in the frame by means

of the shaft 6. A lever formed in two parts 7 and 8, kept together by a hinge 9 and the bolt 10, is fulcrumed in the frame by means of the round bar 11 which is fastened to the 60 part 7 and rests upon the bearing block 12. The upper end of the lever part 8 is connected through the pin 14 to the pitman 15 which is mounted on the crank 16 formed on the driving shaft which is journaled in 65 bearings connected with the frame. The lower end of the lever part 7 is provided with a pressure transmitting convex rolling face formed as a cylinder of which the axis passes through the point A parallel with the 70 bar 11. A cogshaped projection 17 is affixed to the part 7 above the convex face. 18 represents a pressure transmitting block or segment which by means of the round bar 19 is journaled in the jaw 5 at a constant distance 75 from the shaft 6. The segment 18 is formed with a cylindrical rolling face, not necessarily concentric with the bar 19. It is also formed with two lugs 20, arranged to rest during the assembling of the machine 80 on corresponding lugs 29 in the frame for facilitating the mounting of the segment. 21 represents a spring applied between the frame and the jaw and acting so as to press the segment against the convex face of the 85 lever. The bearing of the bar 19 is lubricated through a port 22, and the bearing of the bar 11 from an oilcup 23. The latter bearing is protected from dust and sand by a shield 24 hinged to the lever 7. A lip 25 90 projecting from the jaw 5 above the bar 19 serves to protect the bearing of the segment, which is perforated by openings 26 to permit dust and sand to drop through the segment. 27 represents a bolt or lug extending 95 from the jaw 5 and arranged to prevent the lever part 7 from swinging too far to the left in Fig. 1.

The machine operates in the following manner: The driving shaft to which a flywheel is keyed is put into rotation by suitable motive power. The motion of the shaft is transmitted through the crank 16 and pitman 15 to the lever which receives a swinging motion around its fulcrum 11, so that its upper end oscillates between the positions indicated by 14 and 14'. From the short end of the lever the power is transmitted through the convex face to the segment and to the movable jaw, so that stones fed between the crushing plates become crushed. The segment 18 moves then around its jour-

nal 19 through a very small angle, so that the friction loss at the journal 19 is insignificant. At the line of contact between the segment 18 and the lever 7 there is a true 5 rolling motion, and therefore no friction loss at all.

The machine is intended to be operated at fairly high speed, so that the segment 18 must move with an acceleration which is greater than that due to gravity in order that the segment shall not lose proper mesh with the lever. The said proper mesh, or the correct position of the segment relatively to the lever, would not be lost if a certain 15 minimum pressure could always be maintained between the segment and the lever. But in actual practice this condition cannot be obtained, for the minimum pressure between the segment and the lever depends, not only on the tension of the springs 21, but also on the amount of loose play in the 20 connection between the driving shaft and the lever. The existence of such play will at times cause a lack of proper pressure between the segment and the lever, so that at the moment when the convex face of the lever recedes from the jaw the segment will be apt to lag behind. For this reason the cog 17 is provided in the lever. The cog 25 will come into contact with the segment and restore it to its proper position when it lags behind the lever by reason of insufficient pressure between the segment and the lever.

If the machine should become strongly 30 overloaded for instance by reason of a sledgehammer, dropped by accident or by intention between the crushing plates, the safety bolt 10 will be pulled off so that the motion of the lower part 7 of the lever will instantly cease, while the upper part 8 may 35 continue to move, swinging around the hinge 9 until the flywheel is stopped. When the bolt 10 breaks, the lever part 7 will be moved by the springs 21 so that the hinge 40 9 swings toward the left in Fig. 1. The bolt 27 is provided in order to prevent the hinge from swinging too far in said direction, and thus to occupy any of the space which is necessary for the unobstructed motion 45 of the pitman. It is evident that for this purpose the bolt 27 could just as well be fastened to the frame instead of to the 50 jaw.

The safety bolt 10 is shown in detail in 55 Fig. 5, from which appears that it is formed with two hexagon heads of which the larger one is intended for the screwing of the bolt into the hole at the top end of the lever 7, and the smaller one is intended for removing the broken part of the bolt from the hole. 60 Between the two hexagon heads the bolt is provided with an incision 28 so that its diameter is reduced to proper size, sufficiently large to transmit any legitimate strain, but relatively weaker than any other 65 part of the machine so that it will certainly

break for a strong overload, and save any other expensive part of the structure. It is evident that in order to save weight in the frame, the jaw and the lever, the arrangement ought to be such that the ratio 70 between the pressure on the fulcrum 11 and the pull on the bolt 10 remains constant for any position of the crank or the lever. This will be the case if the following two 75 conditions are fulfilled: the length of the short arm of the lever defined as the perpendicular distance of the fulcrum 11 from the line which passes through the point A and through the point of contact between the segment and the lever shall remain constant for any position of the crank, and the hinge 9 shall be located on the straight line between the bar 11 and the pin 14. The arrangement illustrated in Fig. 1 is such that both of these conditions are substantially 80 filled.

The adjustment of the distance between the crushing-plates is effected by moving the bearing block 12 in the frame and placing fillers of suitable and uniform thickness 85 between the frame and the block. The seat in the frame upon which the bearing block 12 is located must be exactly parallel with the driving shaft, and since this seat cannot readily be finished with ordinary machine 90 tools the frame shown in Fig. 1 is so designed that it admits the milling of the seat by means of a special device mounted in the frame 2, one in the bearings for the driving shaft and the other one in the bearings for the shaft 6.

Having thus described my invention, what I claim is:

1. The combination of a frame, a jaw journaled in the frame, a thrust bar journaled in the jaw at a constant distance from the journal of the jaw, a lever fulcrumed in the frame and formed with a convex face in contact with the thrustbar, a draw spring 105 connection between the frame and the jaw 110 arranged to press the thrustbar against the convex face, and means for oscillating the lever, the convex face being in rolling contact with the thrustbar.

2. The combination of a frame, a jaw journaled in the frame, a thrustbar journaled in the jaw, a lever fulcrumed in the frame and formed with a convex face in rolling contact with the thrustbar, a draw spring 115 connection between the frame and the jaw 120 arranged to press the thrustbar against the convex face, the thrustbar being formed with lugs arranged to rest on corresponding lugs in the frame for facilitating the mounting of the thrustbar.

3. The combination of a frame, a jaw journaled in the frame, a thrustbar journaled in the jaw, a lever fulcrumed in the frame and formed with a convex face in contact with the thrustbar, a draw spring 130

connection between the frame and the jaw arranged to press the thrustbar against the convex face of the lever, the lever being formed with a cog above the thrustbar, and

5 means for oscillating the lever.

4. The combination of a frame, a jaw journaled in the frame, a thrustbar journaled in the jaw, a lever fulcrumed in the frame and formed with a convex face in
10 rolling mesh with the thrustbar, a draw spring connection between the frame and the jaw, a cog carried by the lever for limiting the variation in the mesh between the convex face and the thrustbar, and means
15 for oscillating the lever.

5. The combination of a frame, a jaw journaled in the frame, a lever fulcrumed in the frame and formed with a convex face, a thrustbar journaled in the jaw at con-
20 stant distance from the journal of the jaw and formed with a cylindrical face arranged

to roll upon the convex face, a draw spring connection between the frame and the jaw, and means for oscillating the lever.

6. The combination of a frame, a jaw journaled in the frame, a lever fulcrumed 25 in the frame and formed with a convex face, a thrustbar journaled in the jaw at constant distance from the journal of the jaw and formed with a cylindrical face arranged to roll upon the convex face, of the lever 30 means carried by the lever for limiting the variation in mesh between the convex face and the cylindrical face, a draw spring connection between the frame and the jaw, and means for oscillating the lever. 35

Signed at Stockholm, Sweden, this 25th day of May, A. D. 1918.

TURE GUSTAF RENNERFELT.
